FIG. 4

FIG. 1 is a side elevational view of a container for pulverulent materials or the like embodying my new design, the other side being substantially the same in appearance thereof;

FIG. 2 is an end elevational view thereof, the other side being substantially the same in appearance;

FIG. 3 is a bottom plan view thereof;

FIG. 4 is a top plan view thereof; and

FIG. 5 is a fragmentary sectional view taken on the line 5—5 of FIG. 1.

The dominant features of my design reside in the portions shown in full lines.

I claim:

The ornamental design for a container for pulverulent material or the like, as shown and described.
